GLUING MACHINE

Filed Aug. 17, 1929

FIG. 1

FIG. 2

INVENTOR

Walter Steinmann

BY Edwin W. Hammer
ATTORNEY

UNITED STATES PATENT OFFICE

WALTER STEINMANN, OF BLOOMFIELD, NEW JERSEY

GLUING MACHINE

Application filed August 17, 1929. Serial No. 386,617.

In the preparation of books for binding it is the practice to assemble the component parts or signatures, whether single pages or groups of pages, jog them at their edges to properly even them, and then to apply glue to the backs to fasten such signatures together and prepare the backs for the possible application of a backing strip of paper, muslin or other material. This application of glue 10 has been by manual operation of a brush which has distinct disadvantages: it is slow, and the brush carries an uncertain and varying amount of glue, the distribution of which upon the bristles of the brush cannot be controlled; in addition, this hand operation gives an uncertain and variable penetration of glue between the signatures, causing uncertain or too great adhesion thereof.

To overcome these difficulties I have invented a machine which will apply glue to the backs of books mechanically and secure a regulation of the amount of glue supplied to the backs and an even distribution thereof without smearing with glue the top or bottom 25 edges of the book. My preferred form of such machine is shown in the drawings, in which Fig. 1 is a plan view and Fig. 2 a longitudinal or side elevation in partial section. In these drawings the machine is shown as carried by, 30 or mounted upon, a suitable table 1 having a movable top 2 hinged thereto, as at 3, to permit access to certain parts for cleaning, adjustment, replacement or repair.

The table carries two compartments, 4 and 35 5, serving as glue-pot and water-pot respectively. Each pot preferably contains an electric heater 6 for maintaining the glue at the proper consistency on the one hand and creating vapor on the other hand to soften the 40 brushes (presently to be described) and keep them from accumulating an undesired amount of glue.

In the glue-pot 4 is partially immersed a metal roller 7 with smooth surface, rotatably 45 supported in suitable bearings, and power driven. In juxtaposition to the metal roller 7 is an adjustable scraper 8 for the regulation of the amount of glue carried by the roller 7. The upper surface of the roller 7 projects upwardly through an opening in the table top

2, so that the backs of books may be brought in contact with the roller, as will later be fully pointed out.

Mounted in the water-pot 5, preferably above the level of the water therein, are two 55 rotatable, cylindrical brushes 9 and 10, preferably made in sections so spaced as to permit the bristles to project up between the wires of a grille 11; the extent of such projection is regulated or determined by the vertical adjustment of the wire-supporting bars 12 on their posts 13, carried by the table-top 2, and movable therewith. The brushes 9 and 10 are geared or belted, or otherwise driven, 60 so as to rotate in opposite directions, the right-hand brush 9 rotating clockwise, and the left-hand brush 10 rotating counter-clockwise; the speed of the brush 10 is preferably greater than that of the brush 9, for a purpose presently to be described.

At the right end of the grille 11 is a guide plate 14, adjustable longitudinally, as at 15, to guide the book or group of books A into position to be acted upon by the brush 9; at the left end of the grille 11 is a stop-plate 16, adjustably mounted on the table-top 2, as at 17, to limit the movement of the book or group of books toward the left, as shown at A'.

The brass roller 7 and the rotary brushes 9-10, are preferably driven by power from a shaft 18, such shaft itself being preferably driven from an electric motor 19 or other source of power; in the present instance the motor 19 and the shaft 18 are shown as mounted on or carried by the table 1. The brush 9 is shown with its driving belt twisted to get the reversal of direction of brush 9 with respect to brush 10; as will be seen from the relative sizes of driving pulleys on brushes 9 and 10, the brush 10 rotates faster than brush 9 to compensate for the fact that the books are themselves moved from right to left.

In the operation of the machine the operator takes an assembled set of signatures comprising a book, or several such assemblies if he can grasp them in his two hands, and jogs the edges to even them. He then passes the backs over the glue roller 7, taking care that

neither the front nor the back edges take glue from such roller. He then transfers this same group comprising the book or books down the sloping edge of the guide-plate 14 on to the grille 11, where the rotating brush 9 works the glue evenly over the backs of the books to the back edge and between the signatures, all without smearing glue on the vertical rear faces of the books. The progressive movement of the books is from the position A to the position A', the excess speed of the brush 10 working the glue forward to the front edge of the backs without smearing the forward vertical faces of the books; the proper adjustment of the stop 16 prevents the brush 10 from wiping any glue on the vertical rear faces of the books. It will be noted that the adjustment of the guide-plate 14 gives an initial positioning A of the books with the front edges in advance of the brush 9, so that the brush 9 does not smear the vertical front faces.

What I claim as my invention is as follows:

1. In a gluing machine a table-top having a succession of receptacles, one receptacle serving as a glue-pot and having within it a rotatable glue-applying roller adapted to dip in glue carried therein, over which the object to be glued is passed, and another receptacle in advance of the first serving as a hot-water tank and having rotatably mounted therein a pair of glue-distributing brushes to receive the object upon which glue has been applied by the roller and to distribute the glue so applied.

2. In a gluing machine a table-top having a succession of receptacles, one receptacle serving as a glue-pot and having within it a rotatable glue-applying roller adapted to dip in glue carried therein, and another receptacle in advance of the first serving as a hot-water tank and having within it a pair of rotatably mounted glue-distributing brushes, and means for heating water in such tank.

3. In a gluing machine a table-top having a succession of receptacles, one receptacle serving as a glue-pot and having a glue-applying rotatable roller adapted to dip in the glue carried therein and an adjustable scraper co-operating with the roller to regulate the amount of glue carried thereby, and another receptacle in advance of the first serving as a hot-water tank, means for heating the water in such tank, and a pair of power-driven glue-distributing brushes rotatable above the normal water-level therein.

4. In a gluing machine a table-top having a succession of receptacles, one receptacle serving as a glue-pot and having a rotatable glue-applying roller adapted to dip in the glue carried therein, and another receptacle in advance of the first serving as a hot-water tank, and a pair of power-driven glue-distributing brushes rotatable above the normal

water-level therein, together with a grille over the rotating brushes between the members of which the bristles of the rotating brushes emerge to distribute over the surface of the object to be glued the glue which has been already applied thereto by the glue-applying roller, a guide-plate at one end of the grille and a stop plate at the other end thereof.

5. In a gluing machine a table-top having a succession of receptacles, one receptacle serving as a glue-pot and having a rotatable glue-applying roller adapted to dip in the glue carried therein, another receptacle in advance of the first serving as a hot-water tank and having a pair of power-driven glue-distributing brushes rotatable above the normal water-level therein, and means for heating the contents of each receptacle.

6. In a gluing machine a table-top having a succession of receptacles, one receptacle serving as a glue-pot and having therein a glue-applying roller so rotated that its upper surface travels in a direction similar to that of the surface to be glued, and another receptacle in advance of the first serving as a hot-water tank and having therein a pair of glue-distributing brushes rotatable in opposite directions above the normal level of the water therein, the upper surface of the brush first met by the object being glued moving in a direction opposite to that of such object.

7. In a gluing machine a table-top having a succession of receptacles, one receptacle serving as a glue-pot, and another receptacle in advance of the first serving as a hot-water tank and having therein a pair of glue-distributing brushes rotatable in opposite directions above the normal level of the water therein, the upper surface of the brush first met by the object being glued moving in a direction opposite to that of such object and at a speed less than that of the second brush.

8. In a gluing machine a table-top having a succession of receptacles, one receptacle serving as a glue-pot, and another receptacle in advance of the first serving as a hot-water tank and having therein a pair of glue-distributing brushes rotatable in opposite directions above the normal water-level therein, the upper surface of the brush first met by the object being glued moving in a direction opposite to that of such object and at a speed less than that of the second brush, together with an adjustable grille above the brushes to regulate the penetration of the distributed glue.

9. In a machine for applying glue to the backs of books or the like, a hot water tank in which are mounted two glue-distributing brushes, the first brush rotating with its upper surface moving in a direction opposite to that of the book being glued and the second brush rotating in the reverse direction and at a higher speed than the first brush, a grille

above the brushes between the members of which the bristles of such brushes emerge, a guide plate at one end of the grille along which the book passes, such book having had 5 glue previously applied along the major portion of the back while leaving the ends of the book free of glue, said guide plate being so positioned with respect to the first brush as to make such brush contact with the book back 10 of the forward edge thereof, to distribute the glue toward the back edges and a stop-plate at the other end of the grille so positioned with respect to the second brush as to prevent such second brush from contacting 15 with the rear end of the book while distributing the glue toward the forward end thereof.
